Application November 20, 1950, Serial No. 196,575

2 Claims. (Cl. 204—211)

The present invention relates to improvements in apparatus for progressively electroplating a continuously moving strip of material, for example, a strip of black plate, with a coating of protective metal, such as tin, zinc or the like.

When electroplating elongated strip metal, the strip is continuously progressively moved longitudinally along a path across one or a series of electroplating cells disposed along the path. Each cell contains a bath of electroplating solution and an anode of soluble plating metal disposed in the bath. The position of the strip relative to the anode greatly influences the character of the coating deposited. One problem encountered in plating strip is caused by camber in the rolled strip, which as the strip is moved at a high speed along the path across the cells causes the strip to weave laterally back and forth. This lateral weaving of the strip is very difficult, if not impossible, to prevent. As a result, it is necessary to make the anode wider than the theoretical or optimum width. The wider anode causes the deposition of a heavier coating along the edge of the strip. This phenomenon is commonly referred to as "edge effect." Besides wasting anode metal, the heavy coating along the edges of the strip is undesirable and these edges must be sheared off. Other operational difficulties also are created.

The commercial electroplating line usually has to plate successive lengths of strip having different widths. Accordingly, it has been the customary practice to use an anode wide enough for the widest strip to be plated. As a result, the narrower lengths of strip are plated with an anode that is too wide. This also causes excessive "edge effect." In addition, a number of operational difficulties are created. When a wider anode is used for plating a narrower strip, more metal is removed from the anode at the center portion than the edges so that the anode is deformed. If an attempt is made later to plate a wider strip with the same anode, the edges of the anode are closer to the strip and this in turn results in a non-uniform coating being deposited that is thinner along the center portion and heavier along the side portions. In order to overcome this difficulty, it is customary to schedule operations so that the wider strips are plated first. This only partially answers the problem as the narrower strip is plated with an anode of excessive width.

Accordingly, it is an object of the present invention to provide an improved apparatus for electroplating strip that can electroplate successive lengths of strip of the same and different widths and do this with an anode of the correct width for each length.

It is an object of the present invention to provide an improved apparatus for electroplating strip that will maintain the anode in alignment with strip when the strip weaves back and forth laterally of the direction of strip travel.

It is an object of the present invention to provide an improved apparatus for electroplating strip that will

properly plate successive lengths of strip of different widths and simultaneously maintain the anode in alignment with any lengths of strip which laterally weave.

In accordance with my invention the apparatus for progressively electroplating continuously moving strip includes an electroplating cell containing an anode. The anode preferably comprises one or more elongated anode bars extending across from side to side of the strip. Power actuated means are provided for moving the anode bar to vary the width of the anode. Control means responsive to the strip width is provided to actuate the anode moving means to adjust the width of the anode in accordance with the width of the strip. The anode is supported for movement transversely of the direction of strip travel and is automatically maintained in alignment with the strip upon lateral weaving of the strip.

These and other objects and advantages of the present invention will become more readily apparent from the following detailed description, taken with the accompanying drawings, in which:

Figure 1 is a plan view of a portion of an electroplating line embodying the principles of the present invention;

Figure 2 is a longitudinal sectional view taken along line 2—2 of Figure 1;

Figure 3 is a transverse sectional view taken along line 3—3 of Figure 2;

Figure 4 is a schematic plan view of the electroplating line of Figure 1 and illustrating transverse weaving of the strip;

Figure 5 is a plan view of a portion of the electroplating line of Figure 1 and includes a diagrammatic representation of an electric circuit controlling operation of an electroplating cell;

Figure 6 is a fragmentary sectional view taken along line 6—6 of Figure 2;

Figure 7 is a view similar to Figure 6 illustrating a modification of the apparatus of Fig. 5; and,

Figure 8 is a diagrammatic view illustrating another embodiment of the present invention.

Referring to the drawings and more particularly to Figures 1 to 3 illustrating a portion of an electroplating system embodying the principles of the present invention, a strip S is continuously progressively moved along a path across a series of electroplating cells 10 with the bottom surface 12, the surface to be plated, in contact with an electrolytic bath in each cell. The bottom surface 12 of the strip S is moved across and in electrolytic relation with a soluble anode 11 submerged in the bath of electrolyte in the cell 10. The strip S and anode 11 are connected to a source of electroplating current as the cathode and anode, respectively, so that a layer of anode metal is deposited on the surface 12 which faces the anode.

The means for moving the strip S through the electroplating line may be of any suitable type such as is customarily used in mills for moving strip metal along a path. Power actuated rolls may be used for this purpose. Adjacent the entry end of cell 10, there is a pair of rotatable strip supporting and guiding rolls 13, 14. A similar pair of rolls 15, 16 are mounted adjacent the exit end of the cell. Customarily, in an electroplating line, a pair of these rolls are mounted between each pair of cells and at each end of the line so that there is a pair of rolls at each end of each cell. One roll of each pair, the upper rolls 13 and 15, is an electrically conductive contact roll for connecting the strip as a cathode to a source of electroplating current. As will be more fully hereinafter described, the contact roll 15 and the anode 11 are connected through a control circuit to the opposite sides of a source of electric current. The bottom or lower rolls 14 and 16 are back-up rolls pressing the strip up against the corresponding or respective contact rolls.

13 and 15 so that the contact rolls and the strip will have good electrical contact with each other and so that each pair of rolls will securely grip the strip therebetween. The rolls 13 through 16 may be power driven by any suitable means, not shown, such as is customarily used in steel mills for rotating the rolls which support and move a strip along a predetermined path.

The electroplating cells are identical and only one will be described in detail. Identical portions of the different cells will be identified by the same reference numerals.

The cell 10 includes a tank 18 positioned along the path of the strip S so that the strip passes across the tank 10 from end to end in contact with a bath of electrolyte solution in the tank. As shown, the tank 18 is disposed below the path of the strip and has side walls 19 located on opposite sides of the strip path that extend above the path of the strip to prevent or reduce spillage of the electrolyte. The anode 11 is arranged in electrolytic relationship to the path of the strip surface 12 and comprises a plurality of similar elongated anode elements or bars 20 supported in spaced apart parallel relationship.

The means for supporting the anodes 20 in spaced apart relationship includes a central member 21. A pin 22 is mounted in member 21 and in each anode bar 20 to provide a pivotal connection therebetween. Each bar 20 is swingable about the vertical axis of pin 22, and the axes of all of the pins are located along a line extending parallel to the direction of strip travel. Each pin 22 is located substantially midway between the opposite ends of the respective anode bar. An electrically conductive member 23 extends parallel to member 21 and across the ends of anode bars 20. Between the end of each bar 20 and member 23, there is a pin 24 which fits a recess in the bar and a recess in the member to provide therebetween a pivotal connection. The pivotal connections at the ends of the bars are located along a line parallel to the direction of strip travel and parallel to the line along which the axes of pins 22 are located. Member 23 is movable relative to member 21 to provide parallel linkage movement for the anode bars 20 so that the width of the anode 11 can be adjusted to accommodate lengths of strip of different widths. As shown in Figure 1, when member 23 is moved from the position shown in full lines to the position shown in broken lines, the anode bars 20 are swung about the axes of pins 22 and the width of the anode is reduced. The anode bars 20 are disposed in a plane parallel to the path of the strip surface 12 and are movable about individual axes located in a plane normal to the plane of the strip surface.

A spacing member 26, similar to member 23, extends across and beneath the opposite ends of the anode bars 20 and each bar is pivotally connected to the member 26 by a pin 28, similar to pin 24. It will be noted that pin 28 needs to be rotatable relative to the bar or the member 26. The member 26 is movable relative to member 21 and increases the stability of the anode bars, particularly during movement, and additionally aids in maintaining the bars 20 parallel.

Each member 23 and 26 is connected to a member 30 and 31, respectively. The member 30 is provided with an electrical connecting member or bus bar 32 which is adapted to be connected to a source of electric current and member 31 is provided with a similar connecting member or bus bar 33 for a similar purpose. The members 23, 24, 26 and 28 are electrically conductive and members 24 and 26 are electrically connected to bus bars 32 and 33, respectively. When bus bars 32 and 33 are connected to a source of electroplating current, both ends of each bar 20 are connected to this source. Preferably, either both ends or the middle portion of each anode bar 20 is connected to a source of electroplating current to obtain more uniform distribution of the current density.

The cell 10 includes power actuated means for adjusting the width of anode 11. There is a long lead screw

35 rotatably mounted on the side of tank 18. This screw carries a nut 36 and is connected to a motor 37 which upon energization rotates lead screw 35 to move the nut 36 along the screw. The motor 37 is reversible and the nut can be moved along the screw in either direction. Nut 36 is connected by link 38 to member 23 so that rotation of screw 35 varies the width of anode 11. The anode 11 is widened or narrowed, depending upon the direction of rotation of motor 37 and screw 35 which in turn controls the direction of movement of member 23.

The cell 10 is movable back and forth in a direction transverse to the path of the strip and in a plane parallel to the strip surface. Beneath tank 18, there are a pair of rails 40 mounted on a supporting framework 41. The tank 18 carries flanged wheels 42 mounted on rails 40. A reversible motor 44 is mounted on the framework 41 and connected to a long lead screw 45 which is engaged by a nut rotatably mounted on a bracket 47 connected to the bottom of tank 18. When motor 44 is energized, the lead screw 45 is turned and tank 18 and anode 11 are moved across the path of the strip in a plane parallel to the strip surface. The direction of movement depends on the direction of motor rotation.

The electroplating line includes a control circuit for motors 37 and 44 for varying the width of the anode 10 in accordance with the width of the strip being plated and for moving the anode across the path of the strip to maintain the anode in alignment with the strip. Referring to Figures 5 and 6, a direct current generator for supplying plating current to cell 10 is indicated at 50 with a lead wire 51 going to the bus bar connections 32, 33 of the anode support and a lead 52 going to the contact roll 15. A source of electrical power, such as 200 volt or 440 volt alternating current lines are shown at 53 and 54. These power lines are connected by means of conductors 55 and 56 to a control box A, and by conductors 57 and 58 to a control box B. Power lines 59 and 60 lead from control box A to the motor 44, shown in Figure 3. Power lines 62 and 64 lead from control box B to motor 37.

A source of high frequency energy, for example, 10,000 cycles per second, is shown at 66 with a lead 67 going to the contact roll 15 and a lead 68 going to control box A. The voltage across the high frequency generator is to be applied at two points in control box A, so conductor 68 is shown divided into conductors 69 and 70. Conductors 69 and 70 pass through control box A and by means of conductors 71 and 72 pass to control box B. Conductors 71 and 72 pass through control box B and by means of conductors 73 and 74 are connected to a pair of rubber covered condenser plates 75 and 76, respectively, mounted on tray 18 by brackets 77 and 78 on opposite sides of the path of the strip S.

Within control box A, conventional electrical apparatus is arranged such that current in power lines 59 and 60 applied to motor 44 is controlled in accordance with the relative value of current in conductors 69 and 70. For example, if the current is equal in conductors 69 and 70, no current will be flowing in power lines 59 and 60 and, therefore, motor 44 will not be actuated. If the current in conductor 70 increases over that in conductor 69, motor 44 will operate in one direction. If current in conductor 69 is greater than in conductor 70, motor 44 will operate in the other direction. By this means, the capacitance of each of the condensers formed by the strip S and plates 75 and 76 in the circuits including the high frequency generator 66, the contact roll 15 and the strip S will control the operation of motor 44 to move the tray 18. If more current flows from the strip to plate 75 due to there being a larger area of strip opposed to this plate, the motor 44 is connected so as to move the tray 18 and both plates 75 and 76 until equal areas of the plates are opposed to the strip.

Controller B includes conventional electrical equipment which, by the amplitude of the current in high frequency conductors 73 and 74 will control the current in power

lines 62 and 64. Thus, if large areas of plates 76 and 75 are opposed to strip S passing through the line or, in other words, if the strip is wide, a large amount of high frequency current will pass through conductors 73 and 74. The control apparatus in control box B is of such a nature that this amplitude of current in conductors 73 and 74 will allow impulses of power to be transmitted through power lines 62 and 64 to motor 37, the number of impulses being proportional to the amplitude of the current. In this way, the position of nut 36 on lead screw 35 is controlled in accordance with the area of plates 75 and 76 opposed to the strip S to adjust the width of the anode in accordance with the width of the strip S. If the width of strip S changes, the anode 11 is adjusted accordingly.

Referring to Figure 7, strip responsive solenoids 81 and 82 are used in place of strip responsive plates 75 and 76 to control the amount of current in an auxiliary circuit, such as that generated by the high frequency generator 66 in Figure 5. The amount of current flowing through a solenoid or choke coil is determined by the position of its associated core 83 or 84 which, in turn, depends upon the width or position of the strip. The amplitude of the currents in the auxiliary circuit controls the movements of the tray 18 and the anode 10 as in Figure 5.

Referring to Figure 8 which shows a modified control circuit for adjusting the width of anode 18 in response to variations in strip width and for moving and maintaining the anode in alignment with the strip upon lateral movement of the strip, power lines 86 and 87 are connected to a suitable source of electric current. Control boxes similar to control boxes A and B are indicated at C and D. Electric lights 88 and 89 are disposed along opposite edges of the path of the strip, and each light is connected by wires 90 and 91 to lines 86 and 87. Strip responsive photoelectric cells are indicated at 93 and 94, and each cell has a relatively large area of light reception. The cells 93 and 94 are disposed opposite to lights 88 and 89, respectively. In this modification, control boxes C and D are operated in accordance with the currents generated in photoelectric cells 93 and 94. If the strip tends to weave, one photoelectric cell has its light reduced and the other photoelectric cell has its light increased. Control box C, like control box A, then supplies current to motor 44 to energize the motor and rotate screw 45 to move the anode into alignment with the strip. If the width of the strip changes, becomes wider or narrower, more or less light is transmitted equally to both photoelectric cells 93 and 94, and a current proportional to this change is transmitted through conductors 96 and 97 to control box D, which then imparts a measured amount of power to motor 37 to adjust the anode width in accordance with the strip width. There is a limitation on the amount of anode width control for any given position of the photoelectric cells as a result of the limitation on the width of the area each cell can scan.

The electroplating line is operated continuously and the strip is continuously and progressively moved across the electroplating cells in contact with the bath of electroplating solution in the tank of each cell. Electroplating solution is continuously supplied to each tank. Each tank 18 is provided with an inlet tube 99 connected through a pipe or conduit 100 to a pumping system, not shown. Between the cells 10, there are pans 101 for collecting the overflowing solution and the solution dragged out of the tanks by the moving strip. This solution is returned to a central collector tank, not shown, replenished if necessary and then returned to the cells by the pumping system. The means for circulating the electrolyte solution forms no part of the present invention and the circulating or pumping system may be of a type customarily used for electroplating lines.

When continuously electroplating strip metal, such as steel strip, the moving strip weaves laterally back and

forth and often does not move along a fixed straight path. As shown in Figure 4, which is somewhat exaggerated for purposes of illustration, the strips will move along a path as shown in full lines, and then will move laterally to the path shown in broken lines. This weaving back and forth of the strip may be continuous or intermittent. Heretofore, it has been customary to make the anode wider than the strip and as wide as the path covered by the weaving strip. This is wasteful of anode metal, causes operational difficulties and results in the deposit of excess metal along the edge portions of the strip. In accordance with the present invention, the control circuit includes means operable upon lateral movement of the strip for energizing motor 44 to move the anode 11 into alignment with the strip. If, for example, the strip S weaves or moves laterally from the position shown in full lines to the position shown in broken lines in Figure 4, then the capacitance of condenser plate 75 is increased relative to that of plate 76, or the cores 83 and 84 will be moved to increase the current flowing through solenoid 81 and decrease the current flowing through solenoid 82 or the amount of light reaching cell 93 will be increased and the amount of light reaching cell 94 will be decreased. Upon the occurrence of any one of these conditions, motor 44 is energized to move tank 18 into alignment with strip S. If the strip moves laterally in the opposite direction, the opposite effect is produced by the control circuit and motor 44 is energized to move the cell in the opposite direction into alignment with the strip.

Frequently, successive lengths of the strip will be of different widths with some lengths narrower or wider than others. Customarily, the anode has, in the past, been made wide enough to accommodate the strip of greatest width and the same anode is then used for the narrower lengths of strip. This also causes operational difficulties, wastes anode metal, and causes an excessive deposit of anode metal along the edges of the strip. In accordance with the present invention, the control circuit includes means for energizing the motor 37 in response to a change in strip width for varying the width of the anode in accordance with the width of the strip.

In operation, the strip is continuously moved along the line across the electroplating cells. The anode has a maximum width equal to or greater than the widest strip to be plated, the anode bars 20 will be arranged as shown in full lines in Figure 1 with each bar extending across from edge to edge of the strip. If the next length of strip is relatively narrow, the capacitance of condenser plates 75 and 76 will be decreased or the position of cores 83 and 84 will change to reduce the current flowing through the solenoids, or the amount of light reaching the photoelectric cells will increase and each of these conditions will result in energization of motor 37 and cause the nut 36 to move inwardly along screw 35 to the position shown in broken lines. This causes parallelogram movement of the anode bars 20 about the axes of pins 22 to reduce the width of anode 11. If the next length of strip is wider, the effect is reversed and the motor 37 is energized to move nut 36 out along screw 35 to widen the anode. Thus, the width of the anode is automatically adjusted and maintained in correct relationship to the strip.

The present apparatus is primarily intended for plating strip steel, such as black plate, with a coating of protective metal such as tin, but the apparatus may be used for plating other strip metal with coating of other metal or metals.

I claim:

1. Apparatus for progressively electroplating a surface of successive lengths of strip of the same and different widths, the apparatus comprising tank means including means for containing a bath of electroplating solution, means for longitudinally moving the strip along a path across the tank means with the surface to be electroplated in contact with the solution in the tank means, an anode comprising a plurality of elongated anode elements, means

7
 for connecting the anode and the strip to a source of electroplating current as anode and cathode, respectively, anode supporting and spacing means supporting the anode elements in the tank means with the anode elements extending transversely of and from side to side of the path of the strip in spaced apart parallel relationship, the anode elements being rotatable about individual axes located in a plane normal to the path of the strip, said plane being parallel to the direction of strip travel, the supporting and spacing means including movable means engaging the anode elements and being movable in opposite directions parallel to the direction of strip travel for rotating the anode elements about the axes to vary the width of the anode while maintaining the anode elements parallel, a reversible electric motor carried by the tank means and connected to the movable means and operable upon energization to move the movable means in either opposite direction, an electric circuit means for connecting the motor to a source of electric current, and control means interposed in the circuit means for controlling the operation and direction of rotation of the motor, said control means including a first sensing means positioned along one side of the tank means in the region of one side of the path of the strip, a second sensing means positioned along the other side of the tank means in the region of the path of the other side of the strip, the first and the second sensing means extending from the respective sides of the tank means a substantial distance transversely inwardly beyond respective sides of the path of the strip, the first and second sensing means being operable to produce control signals responsively to the degree the sensing means overlie respective sides of the path of the strip, and means operable responsively to the control signals produced by the first and second sensing means for controlling the electric circuit means whereby the movable means are moved in a direction to increase or decrease the width of the anode responsively to a decrease or an increase in the width of the paths of the strip.

2. Apparatus for progressively electroplating a surface of successive lengths of strip of the same and different widths, the apparatus comprising tank means including means for containing a bath of electroplating solution,
